UNITED STATES PATENT OFFICE.

HORACE JOHNSON CARTER, OF WILMINGTON, DELAWARE, ASSIGNOR TO CHARLES TAYLOR, OF KEARSLEY, MANCHESTER, ENGLAND.

FABRIC PILER.

Application filed September 13, 1926. Serial No. 135,256.

This invention relates to fabric pilers and more particularly to a device of this character adapted for use in piling material to be bleached or dyed in a kier.

5 In bleaching operations it is desirable to have the material uniformly arranged in the kier in order that the bleaching material may have substantial equal access to all portions of the material to be bleached to prevent an uneven bleaching operation, and it is an important object of the present invention to evenly pile the cloth or other material in the kier to permit an even bleaching operation and to prevent the material from knotting or otherwise becoming tangled in the kier.

10 A further object is to provide a fabric piler which is adapted to be used in connection with bottle kiers, but which is readily adapted for use in piling the fabric in any form of open top kier.

15 A further object is to provide a cloth chute which is pivoted to permit its lower end to swing toward and away from the center of the kier, the chute being adapted to revolve simultaneously with the swinging action so that the cloth or other material will be piled evenly in the kier.

20 A further object is to provide a novel form of drive mechanism for swinging and rotating the chute.

25 A further object is to provide a chute which readily may be removed from its supporting structure.

30 Other objects and advantages of the invention will become apparent during the course of the following description.

35 In the drawings I have shown several embodiments of the invention. In this showing:

Figure 1 is a side elevation of the device, Figure 2 is a plan view, parts being omitted;

Figure 3 is a central vertical sectional view on line 3—3 of Figure 2;

40 Figure 4 is a fragmentary detail of a portion of the cam;

Figure 5 is a detail perspective of a portion of the actuating mechanism for swinging the chute;

45 Figure 6 is a fragmentary plan view of a modified form of chute revolving mechanism;

Figure 7 is a detail section on line 7—7 of Figure 6, and,

50 Figure 8 is a detail section on line 8—8 of Figure 2.

Referring to the drawings, the numeral 10 designates a relatively flat support as a whole including a substantially circular portion 11 having an extension 12 at one side thereof. Brackets 13 are carried by the support and are provided at opposite ends with down-turned ends 14 carrying stub axles 15. Flanged wheels 16 are carried by the stub axles and are adapted to travel upon suitable rails 17 whereby the device may be brought into position above either of a number of kiers. The circular portion 11 of the support is provided with a plurality of cams 18 at its inner edge for a purpose to be described.

55 A rotatable ring 19 is arranged over the circular portion of the support concentric therewith, and this ring is provided on its outer edge with gear teeth 20 for a purpose to be described. A plurality of bearing brackets 21 are secured to the support by bolts or the like 22, and these brackets are forked to provide upper and lower bearing arms 23 and 24 adapted to engage the upper and lower edges of the ring 19 whereby the latter is rotatably supported above the ring 11. The ring 19 is provided on its inner edge with diametrically opposite recessed lugs 25, adapted to receive the outer ends of stub shafts 26.

60 A chute 27 projects upwardly through the ring 19 as clearly shown in Figures 2 and 3. This chute includes a bottom 28, preferably tapered to decrease in width toward its lower end as shown in Figure 2, and further includes side walls 29. A bracket 30 extends across the lower face of the chute bottom 28 and is riveted or otherwise secured thereto as indicated at 31. Opposite ends of the bracket 30 are turned upwardly as at 32 and are secured to the stub shafts 26 by nuts 33. It will be apparent that the stub shafts 26 are 65 rotatable in the bearing lugs 25, whereby the chute is adapted to swing about the axes of the bolts 26 and since the greater weight of the chute is beneath the stub shafts, the chute tends to assume a vertical position.

70 Means are provided for rotating the ring 19. As shown in Figures 2 and 3, a motor 34 is arranged over the extension 12 and is secured thereto by bolts or the like 35. This motor is provided with the usual armature shaft and a worm 36 is secured to this shaft. A bearing indicated as a whole by the numeral 37 is arranged over the support 10 inwardly of the motor and the bearing is provided at opposite ends with upstanding bearing arms 75

100

105

110

38 rotatably supporting a shaft 39. A worm wheel 40 is secured to one end of the shaft 39 and meshes with the worm 36 to be driven thereby, and another worm 41 is secured to 5 the opposite end of the shaft 39. A vertical shaft 42 is secured to the support 10 by a nut 43 threaded on the lower end thereof. The shaft 42 rotatably supports a sleeve 44 to which is keyed or otherwise secured a worm 10 wheel 45 meshing with the worm 41. A pinion 46 is also keyed to the sleeve 44 to be driven with the worm wheel 45, and the pinion 46 meshes with the gear 20 carried by the ring 19.

15 Means are provided for positively swinging the chute about the axes of the stub shafts 26 as the ring 19 is revolved. As shown in Figures 1, 3 and 5, a bracket 47 is riveted or otherwise secured against the bottom 20 of the bracket 30 and is provided with a pair of arms having eyes 48 in their ends to receive a pin 49. The pin 49 and one of the eyes 48 are provided with registering openings 50 to receive a cotter pin 51 to prevent 25 displacement of the pin 49, and a small chain 52 or other flexible element, secures the pin 51 against loss when it is removed for a purpose to be described. A similar flexible element 53 is secured to one end of the pin 49 for a 30 like purpose. A toggle 54 is employed for swinging the chute 27. This toggle consists generally of a turn buckle having a central sleeve 55 provided with oppositely threaded openings in its ends. A counter weight 54' 35 is employed for maintaining the sleeve in any adjusted position as will become apparent. The threaded rod 56 is arranged in one end of the sleeve 55 and is provided at its end with an eye 57 receiving the pin 49 between the 40 arms of the bracket 47. A rod 58 also is threaded in the opposite end of the sleeve 55 and is provided at its end with a yoke 59 through which passes a bolt 60. A bearing 61 is arranged adjacent the yoke 59 and is 45 provided with an extension 62 arranged between the arms of the yoke and receiving the bolt 60 whereby the toggle is pivotally connected to the bearing 61. The outer end of the toggle is adapted to swing laterally under 50 conditions to be described, and accordingly the eye 57 loosely surrounds the pin 49 to permit this action to take place. A supporting arm 63 is pivotally connected to the ring 19 as at 64, the opposite end of the arm 63 being arranged over the bearing 61. A roller 65 is arranged over the last mentioned end of the arm 63 and a bolt 66 pivotally connects the bearing 61, arm 63 and roller 65 to each other. The roller 65 is adapted to bear 60 against the cams 18 to effect inward movement of the lower end of the chute in a manner to be described, the roller being shown in contact with the cams in Figure 3 of the drawings.

65 In Figures 6 and 7 of the drawings I have

shown a somewhat modified form of drive for the ring 19. In this form of the invention I also provide a bearing 67, somewhat similar to the bearing 37 previously described. This bearing has an extension 68 carrying a bearing sleeve 69 in which is rotatably mounted a shaft 70 provided at its outer end with a pulley 71. The shaft 70 is provided inwardly of the bearing sleeve 69 with a worm 72 meshing with a worm wheel 73. The wheel 73 is keyed or otherwise secured to a sleeve 74 rotatable upon a shaft 75, the latter being secured to the support 10 by a nut 76. A pinion 77 is also secured to the sleeve 74 to rotate with the wheel 73 and this pinion meshes with the gear 20. It will be apparent that either form of the device may be used depending upon whether it is desired to rotate the ring 19 by an electric motor or belt drive.

70 The operation of the apparatus is as follows:

The piler as a whole is moved upon the rails 17 to place it above the desired kier whereupon the chute 29 is lowered into position. The chute is readily removable merely 90 by withdrawing the cotter pin 51 and pin 49 to disconnect the toggle from the bracket 47. The lugs 25 are provided with open tops to permit the chute to be lifted upwardly, the weight of the chute being depended upon to 95 retain the stub shafts 26 in position while the device is operating. When the motor is operating, rotation of the worm 36 transmits a rotary motion to the worm wheel 40 and worm 41, rotation of the worm 41 driving the 100 worm wheel 45. Since the worm wheel 45 rotates with the pinion 46, it will be apparent that the ring 19 will be driven, the speed of rotation of the ring being slow due to the reducing gearing employed. Rotation of the 105 ring 19 causes the chute also to be rotated due to the connection between these members. As the chute rotates, the roller 65 travels over the cams 18, the high points of the latter forcing the roller inwardly to swing the lower end of the chute upwardly. After the roller passes the high point of each cam, the weight of the lower end of the chute causes the latter to swing downwardly until the roller engages the next successive cam. The arm 63 is employed merely to hold the roller 65 in proper position in engagement with the cams 18. As the roller moves inwardly and outwardly over the cams it causes the upper end of the toggle to move laterally, as indicated in dotted lines 110 in Figure 2 of the drawings, this movement being caused by the swinging of the free end of the arm 63 about its pivot point 64. The eye 57 loosely surrounds the pin 49 to permit the movement referred to. The movement of the lower end of the chute may be varied by turning the sleeve 55 which obviously 115 changes the throw of the lower end of the chute by changing the distance between the point of contact of the roller 65 against the 120

125

5 cams and the center of the pin 49. The weight 54' is provided merely to hold the sleeve 54 in any given adjusted position. Any number of cams 18 may be employed and these cams 5 may be shaped as desired. As the device is 10 illustrated, the ring 19 is adapted to rotate in a counter-clockwise direction and the shape of each cam is such that movement of the lower end of the chute toward the outside of the 15 kier will be somewhat slower than the movement toward the center of the kier, but the invention is not limited to the particular cams employed, as will be apparent. While I have 20 shown brackets 21 for rotatably supporting 25 the ring 19, it will be apparent that any suitable supporting means may be employed.

In practice it is preferred to employ the motor 34 for operating the device, but the form of the device illustrated in Figures 6 20 and 7 may be employed if it is desired to use 25 a belt drive.

It is to be understood that the forms of the invention herewith shown and described are to be taken as preferred examples of the same 25 and that various changes in the shape, size and arrangement of parts may be resorted to without departing from the spirit of the invention or the scope of the subjoined claims.

I claim:

30 1. A fabric piler comprising a chute, a substantially circular stationary member having a plurality of inwardly extending cams, a rotatable member carried by said stationary member and pivotally supporting said 35 chute, means engaging said rotatable member for rotating said chute relative to said circular member, and operating connections between said chute and said cams to move the former as said chute is rotated relatively to 40 said circular member.

45 2. A fabric piler comprising an angularly arranged chute pivotally supported intermediate its ends, a substantially horizontal circular stationary member provided with inwardly extending cams, a rotatable member carried by said stationary member and supporting said chute, means engaging said rotatable member for rotating said chute about the axis of said circular member, and operating 50 connections between said cams and said chute to oscillate the latter about its pivot as it is rotated.

55 3. A fabric piler comprising an angularly arranged chute pivotally supported intermediate its ends, a horizontal substantially circular stationary member having a plurality of inwardly extending cams, a rotatable member carried by said stationary member and supporting said chute, a member adapted 60 to contact with the surfaces of said cams, and connections between said last named member and said chute for oscillating the latter about its pivot as it is rotated.

65 4. A fabric piler comprising an angularly arranged chute, means for pivotally support-

ing said chute intermediate its ends, a substantially circular stationary supporting member for said chute provided with a plurality of inwardly extending cams, a rotatable member carried by said stationary member and carrying said pivot means, a member adapted to contact with said cams, and connections between said last named member and said chute for oscillating the latter about its pivot as it is rotated. 75

5. A fabric piler comprising an angularly arranged chute, a substantially circular supporting member provided with inwardly extending cams, a rotatable member pivotally supporting said chute intermediate its ends, means for supporting said rotatable member on said supporting member, and means connected between said cams and said chute for oscillating the latter about its pivot as the latter rotates with said rotatable member. 80 85

6. A fabric piler comprising a substantially circular supporting member provided with a plurality of inwardly projecting cams, a rotatable member arranged concentric with and parallel to said supporting member, means carried by said supporting member for supporting said rotatable member, a pair of diametrically opposite bearings carried by said rotatable member, a chute pivotally supported intermediate its ends by 90 95 said bearings, means connected between said chute and said cams for oscillating said chute as it is rotated, and means for rotating said rotatable member.

7. A fabric piler comprising a supporting member provided with a plurality of inwardly extending cams, a ring arranged concentric with and parallel to said supporting member, means carried by said supporting member for rotatably supporting said ring, 100 105 a pair of diametrically opposite bearings carried by said ring, a pair of stub shafts arranged in said bearings, a chute angularly arranged with respect to said ring and secured to said stub shafts, a member contacting with said cams, and connections between said last named member and said chute for oscillating the latter about the axes of said stub shafts as said ring is rotated. 110

8. A fabric piler comprising a horizontal 115 supporting member provided with a plurality of inwardly projecting cams, a ring arranged concentric with and parallel to said supporting member, bearings carried by said supporting member and rotatably supporting said ring, a pair of diametrically opposite open topped bearings carried by said ring, 120 125 a pair of aligned stub shafts supported in said bearings, a chute angularly arranged with respect to said ring and carried by said shafts, and means connected to said chute and having a portion contacting with said cams for oscillating said chute about the axes of said stub shafts as said ring is rotated.

9. A fabric piler comprising a horizontal 130

substantially circular supporting member provided with a plurality of inwardly extending cams, a ring arranged concentric with and parallel to said supporting member, means for rotatably supporting said ring on said supporting member, said ring being provided on its outer surface with gear teeth, a pinion carried by said supporting member and meshing with said gear teeth, a pair of diametrically opposite open topped bearings carried by said ring, a pair of aligned stub shafts pivotally supported in said bearings, a chute projecting through said ring at an angle thereto, a bracket carried by said chute and connected at its ends to said stub shafts, a roller contacting with said cams, and connections between said roller and said chute.

10. A device constructed in accordance with claim 9 provided with means carried by

said ring for supporting said roller in contact with said cams. 20

11. A device constructed in accordance with claim 9 provided with an arm pivotally connected at one end to said ring, the opposite end of said arm being pivotally connected 25 to said roller.

12. A device constructed in accordance with claim 9 provided with means for varying the length of the connections between 30 said roller and said chute.

13. A device constructed in accordance with claim 9 wherein the connections between said roller and said chute include a turn 35 buckle having a rotatable portion for varying the length of said connections.

In testimony whereof I affix my signature.

HORACE JOHNSON CARTER.
